UNITED STATES PATENT OFFICE.

PETER RADOMAN, OF RED LODGE, MONTANA.

RAILROAD JOINT-CHAIR.

971,308.

Specification of Letters Patent. Patented Sept. 27, 1910.

Application filed March 29, 1910. Serial No. 552,139.

To all whom it may concern:

Be it known that I, PETER RADOMAN, a citizen of the United States, and a resident of Red Lodge, in the county of Carbon and State of Montana, have invented a new and Improved Railroad Joint-Chair, of which the following is a full, clear, and exact description.

The purpose of this invention is to provide a railroad joint chair of novel form, that adapts it to incase the base flanges and webs of two track rails at adjacent ends thereof; and also to provide means for securing the improved chair on the rails so as to render them practically continuous and perfectly alined, thereby preventing any jar at the rail joints when traversed by heavy trains.

A further purpose is to provide novel means such as improved spikes, for securing the rails in position on the cross ties of a road bed, which will prevent the rails from becoming loose and thus obviate danger of accident from such a cause.

The invention consists in the novel construction of parts and their combination, as is hereinafter described and defined in the appended claims.

Reference is to be had to the accompanying drawings, forming a part of this specification, in which similar characters of reference indicate corresponding parts in all the views.

Figure 1 is a perspective view of the improved chair and spike applied for securing the meeting ends of two track rails upon a cross tie of a railroad; Fig. 2 is a transverse sectional view, taken substantially on the line 2—2 in Fig. 1; Fig. 3 is a perspective view of the improved railroad chair; and Fig. 4 is a perspective view of the improved railroad spike.

In the drawings that show the construction and application of the invention, A, A, indicate end portions of track rails having the usual T-shape in cross section, each embodying a head or ball, two base flanges A', A', and a web portion A², that integrally connects the flanges with the head, the latter overhanging the web as shown in Figs. 1 and 2.

The improved chair embodies a base plate B, having proper width to receive the pair of base flanges A', of each track rail. The side edges of the base plate B are integrally joined to lower portions of two upwardly

and inwardly inclined flanges B', that in service have loose contact with the upper faces of the base flanges A', A'. Upon the upper edges of the inclined flanges B', two vertical flanges B² are integrally formed, having parallel inner surfaces that are spaced apart a distance which adapts them to loosely embrace the sides of the webs A², on two track rail ends, when the latter are inserted an equal distance within the shoe-like track rail chair. Four spaced perforations a, are formed oppositely in each vertical flange B², and register with similar perforations formed in the rail webs A², when the end portions of the similar track rails are inserted an equal distance within the opposite ends of the chair. Through the flanges B², and the webs A², four similar bolts C, are inserted, said bolts having heads C' thereon, at like ends, and threads on their opposite ends, whereon nuts C² are screwed, when the bolts C have been fully inserted through the flanges B², and the intervening webs A².

It will be seen that the end portions of the track rails will be exactly alined when they are inserted and secured within one of the improved chairs, and thus will be prevented from vertical or lateral displacement when seated and secured on the cross ties D, as indicated in Figs. 1 and 2.

A preferred means for securing the chairs of a track line upon the cross ties, consists of spikes shaped as shown in the drawings. The body of the improved spike, as shown at E in the drawings, is rectangular in cross section, and at one end is pointed by beveling its four sides till they meet at the free extremity of the spike body, as shown at b, in Figs. 2 and 4. Upon the opposite end of the body E, a rectangular flange E' is integrally formed, but projects from one side of the said body and produces a head thereon. On the four corners c of the spike body, spaced teeth c' are formed that are inclined upwardly and outwardly, and thus are adapted for hooked engagement within the tie body into which said spike is driven.

In the inclined flanges B', and base plate B, vertical perforations d are formed, that are rectangular in contour, and are so proportioned in size that the bodies E of a similar number of spikes may be inserted downward therethrough and fit loosely therein. In each perforation d an offset rectangular enlargement d' is laterally formed,

said enlargements being located in the sides of the perforations that are parallel with and adjacent to the vertical flanges B^2 and having their bottom walls beveled, and as 5 appears in Fig. 2, the head E' , on a respective spike body E , will occupy the offset enlargement d' , and be completely embedded therein when the spike body is fully inserted down into a cross tie whereon the chair is 10 seated.

As shown in Figs. 2 and 4, the body of the improved spike is bent so as to slightly curve it laterally, thus rendering the outermost side of each spike body concave, and 15 the side thereof that is below the head flange E' convex.

It will be apparent, that the rails forming a railroad track, if secured in place on the cross ties by means of the improved chairs 20 and spikes, will be so fixed in place, that they cannot be accidentally displaced, and the track rails will be held parallel with each other under all conditions of service.

Having thus described my invention I 25 claim as new, and desire to secure by Letters Patent:—

1. A railroad track rail chair, consisting of a base plate, inclined flanges on the side

edges of the base plate, and parallel spaced flanges vertically projecting from the inner 30 edges of the inclined flanges, said base plate and inclined flanges having rectangular vertical perforations therein, said perforations having offset rectangular enlargements extended toward and adjacent to the vertical 35 flanges, said enlargements having beveled bottom walls.

2. In combination, a railroad track rail chair, having a base; two inwardly and upwardly inclined flanges and two vertical 40 flanges and provided with rectangular perforations in the base and inclined flanges, said perforations having offset rectangular lateral extensions, the bottom walls of which are beveled, and railroad spikes having rectangular bodies, each spike having an offset and inclined head that occupies and fits the offset enlargement or lateral extension of a 45 respective perforation.

In testimony whereof I have signed my 50 name to this specification in the presence of two subscribing witnesses.

PETER RADOMAN.
